United States Patent Office

Des. 209,225

Patented Nov. 14, 1967

209,225

CUP

Paul Davis, Swampscott, Mass., assignor to Sweetheart
Plastics, Inc., Wilmington, Mass., a corporation of Maryland

Filed Sept. 2, 1966, Ser. No. 3,700

Term of patent 14 years

(Cl. D44—9)

FIG. 1

FIG. 3

FIG. 1 is a side view partly in cross section of a cup showing my new design;

FIG. 2 is a bottom plan view thereof; and

FIG. 3 is a side view partly in cross section of a second embodiment of a cup showing my new design.

I claim:

The ornamental design for a cup, as shown and described.
